PNEUMATIC TIRE

Charles M. Chupa, Dearborn Heights, Mich., assignor to
United States Rubber Company, New York, N.Y., a
corporation of New Jersey

Filed Sept. 1, 1966, Ser. No. 3,679

Term of patent 14 years

(Cl. D90—20)

Fig. 1

FIG. 1 is a perspective view of a pneumatic tire embodying my new design, it being understood that the full line portion is repeated throughout the circumference of the tire shown by means of broken lines;

FIG. 2 is an enlarged fragmentary side elevational view of the full-line portion shown in FIG. 1;

FIG. 3 is an enlarged fragmentary plan view of the full-line portion shown in FIG. 1;

FIG. 4 is a sectional view taken substantially on the plane indicated by line IV—IV in FIG. 3;

FIG. 5 is a detailed sectional view taken substantially on the plane indicated by line V—V in FIG. 2; and

FIG. 6 is another detailed sectional view taken substantially on the plane indicated by line VI—VI in FIG. 2.

The dominant features of my design reside in those portions shown in full lines in the drawings.

I claim:

The ornamental design for a pneumatic tire, substantially as shown and described.
